UNITED STATES PATENT OFFICE.

CHARLES P. SCHULTZ, OF PAWTUCKET, RHODE ISLAND.

DENTAL MIXING-MORTAR.

SPECIFICATION forming part of Letters Patent No. 737,287, dated August 25, 1903.

Application filed December 4, 1902. Serial No. 133,935. (No model.)

To all whom it may concern:

Be it known that I, CHARLES P. SCHULTZ, a citizen of the United States, residing at Pawtucket, in the State of Rhode Island, have invented a new and useful Improvement in Dental Mixing-Mortars, of which the following is a specification.

In triturating and mixing amalgam and other plastic dental fillings as heretofore performed a small cup-formed mortar has been employed in the use of which the mixture becomes spread and adheres to the inner side and bottom of the mortar in a thin layer, and in order to gather this into a convenient form for use an additional instrument has to be employed to scrape the mixture from the mortar and pestle, and one of the advantages of my improved mixing-mortar consists in the fact that the mixture is so confined in a tube as to be operated upon in a space commensurate with the small quantities of material usually employed for the purpose, the size of an ordinary filling seldom exceeding that of a pea, and by confining the mass in a space just large enough for its proper manipulation the trituration and mixing of the materials is greatly facilitated.

Another advantage of my improvement consists in the fact that the quantity of the substances in the mixing-mortar can be readily determined by means of a graduated scale marked on the surface of the mortar, whereby the employment of special means for measuring such quantities is rendered unnecessary.

In the accompanying drawings, Figure 1 represents the side elevation of the tube of a mixing-mortar embodying my invention. Fig. 2 represents an axial section showing the pestle in position for use with the lower end of the tube of the mortar closed by means of a removable stopper. Fig. 3 represents an axial section of the same with the pestle removed and both ends of the tube closed by means of removable stoppers. Fig. 4 represents a side view of the pestle removed from the mortar. Fig. 5 represents a view of the mixing end of the pestle. Fig. 6 represents a view of the beating end of the pestle. Fig. 7 represents an axial section showing the combination of the glass tube of the mortar with an outer casing. Fig. 8 represents a side view

of the same, showing the graduations and the opening on the side of the casing. Fig. 9 represents an axial section showing a modification of the tube of the mortar in which but one of the end apertures is made funnel-shaped, the opposite ends of the tube being provided with suitable removable stoppers.

In the drawings, A represents a tube made of glass or other transparent material, provided at its opposite ends with the flaring apertures b b, to which the stoppers c c are fitted. The bore d of the tube A is made of uniform diameter, and the body portion e of the pestle B is made to loosely fit the bore d. One end of the pestle is provided with the chisel-shaped mixing-head f and the opposite end with the beating-head g. The tube A is also provided with the graduation j, by means of which the quantity of material introduced into the mortar may be readily determined.

In operating with my improved mixing-mortar the lower end of the tube A is to be closed with the stopper c, which thus constitutes the removable bottom of the mortar. The ingredients to be mixed and triturated are then to be conveyed through the flaring aperture b at the upper end of the tube A into the said tube, the necessary quantities for the mixture being observed and determined by means of the graduated scale j, marked on the outer surface of the tube. The wedge-shaped head f of the pestle B is then inserted into the upper end of the tube A, and by operating the same against the sides of the tube and in the direction of the bottom stopper c, which forms the floor of the mortar, the trituration and mixing may be performed, and in accordance with the quality and texture of the substances to be operated upon either the wedge-shaped head f or the beating-head g may be used in connection with the removable bottom stopper c, and when it is desirable to reverse the ends of the mortar during the operation the pestle B is to be withdrawn and the open upper end of the tube closed by means of a stopper c, as shown in Fig. 2, so as to prevent the spilling of the contents of the tube during its reversal end for end, and after reversing the ends of the tube A the stopper c, which was formerly at the lower end of the tube A and is now at the upper end, is to be removed for the proper

reinsertion of the pestle B and the operation of mixing and trituration continued, the reversal of the mortar end for end being performed as often as required, and by this 5 means that portion of the material first deposited at the bottom of the mortar, and therefore most distant from the action of the pestle, is by the turning of the mortar brought to the upper surface and into direct contact 10 with the head of the pestle, and the trituration and mixing of the mass by this means will be more quickly and thoroughly performed than when operated upon from one side only. The whole mass after being trituated and mixed forms a homogeneous lump, which as such can be readily removed upon the removal of the stopper c, which forms the floor of the mortar. The tube A may be provided with a protective casing C, of metal 15 or other suitable material, as shown in Fig. 20 7, the said casing being provided with side openings k k, through which the graduations j may be observed, and the tube A instead of being provided with funnel-shaped apertures

at both of its ends may be provided with but 25 one funnel-shaped aperture, the other aperture being of the diameter of the bore of the tube, the said ends being provided with suitable removable stoppers, as shown in Fig. 9.

I claim as my invention—

1. In a tubular mixing-mortar, the combination of a glass tube provided with a flaring opening at one of its ends, with removable end-closing means, whereby the ends of the mortar may be reversed and the mass contained therein be alternately operated upon at the opposite ends of the mortar. 30

2. In a mixing-mortar, the combination of the tube provided with a flaring aperture at one of its ends, and a removable stopper for 35 closing the opposite end, with the pestle provided at one end with the chisel-shaped mixing-head, and at the other with the beating-head. 40

CHARLES P. SCHULTZ.
